[57] ABSTRACT

Yarn take-up for winding cheese-type packages in which a large diameter drive roll imparts rotation to one, two or more yarn packages mounted on bobbins spaced apart around the periphery of the drive roll. Yarn is conducted through a traverse guide and a small diameter roll serves as a print roll between the traverse guide and the surface of the drive roll. The print roll is driven by the drive roll and preferably the yarn passes from the print roll around the front side of the drive roll where it is wound on the respective bobbins.

FIG. 1

FIG. 2

YARN TAKE-UP

BACKGROUND OF THE INVENTION

This invention relates to yarn take-up methods and apparatus and, more particularly, to methods and apparatus for winding yarn in a traverse pattern in yarn packages.

In producing synthetic yarns in accordance with conventional practice, the yarn passes through a reciprocating traverse guide. The yarn then passes onto the surface of a drive roll. A bobbin is mounted for rotation about an axis parallel the drive roll axis, so that the yarn wound on the bobbin engages the surface of the drive roll. As the drive roll rotates, it drives the bobbin, and the yarn on the surface of the drive roll passes through the nip between the yarn package and the drive roll. As the yarn package builds, the surface speed remains constant and the bobbin axis moves progressively away from the surface of the drive roll to accommodate the increase in diameter of the package. An example of apparatus for winding yarns in this manner is disclosed in U.S. Pat. No. 3,355,116, issued Nov. 28, 1967.

In order to increase the capacity of yarn take-up machines, while conserving space, it has been customary to mount a pair of bobbins in position for the yarn package on each bobbin to engage the surface of a single drive roll. The drive roll imparts rotation to both bobbins and the yarn from the traverse guide is "printed" on the surface of the drive roll to achieve a uniform traverse wound yarn package. The drive roll thus serves as a print roll.

In order to facilitate removal of the yarn package, typical yarn take-up machines of this type have the bobbin chucks mounted at the front side of the drive roll, where they are readily accessible. The yarn traverse guide is positioned adjacent the rear of the drive roll and the yarn is printed on the rear side of the drive roll and is carried on the surface of the drive roll to the bobbins at the front. This arrangement effectively controls the yarn pattern in the yarn that is wound in the package, but this arrangement makes it more difficult to lace the yarn.

Another problem encountered with attempting to wind two yarn packages with a single drive roll is that the diameter of the drive roll must be relatively large to provide the necessary spacing between the packages. If the yarn traverse guide is positioned to allow lacing the yarn over the top of the drive roll, the traverse guide cannot be positioned close to the surface of the drive roll and, consequently, a long length of uncontrolled yarn extends between the guide and the drive roll. Such an arrangement leads to variations in the pattern of yarn that is wound in the yarn packages.

SUMMARY OF THE INVENTION

Accordingly, it is an object of this invention to provide an improved yarn take-up for simultaneously winding a pair of yarn packages with a single drive roll.

A further object of this invention is to provide a yarn take-up method and apparatus in which the yarn can be laced conveniently over the front of the drive roll.

An additional object of this invention is to provide a conveniently located take-up which is equipped with a large diameter bobbin drive roll which provides ample room for the winding and accommodating yarn packages having large diameter for maximum weight.

Another object of this invention is to provide method and apparatus for winding yarn on bobbins from a single drive roll in which the yarn is effectively controlled between the traverse guide and the surface of the drive roll.

A still further object of this invention is to provide means for maintaining proper yarn winding tension on yarn package while permitting the yarn to have a different level of tension, preferably smaller, upstream of the winding operation.

A yet other object of this invention is to provide a configuration of take-up equipment that is particularly suitable for the adaptation to fully automatic doffing operations.

These objects are accomplished in accordance with a preferred embodiment of the invention by a yarn take-up having a large diameter drive roll. On the front side of the drive roll, upper and lower bobbin chucks are mounted for movement toward and away from the drive roll. The bobbin chucks support the bobbins in position to be driven by the drive roll. A yarn traverse guide is positioned adjacent the rear side of the drive roll and a small diameter print roll is mounted for rotation on a pivoted arm. The print roll extends parallel to the axis of the drive roll and is interposed between the traverse guide and the surface of the drive roll. A drive ring on the drive roll imparts rotation to the print roll in a direction opposite to that of the drive roll. The yarn passes through the traverse guide and is applied directly to the surface of the print roll, from which it passes to the surface of the drive roll, and subsequently to one or the other of the yarn packages that are being rotated by the drive roll.

DESCRIPTION OF THE DRAWINGS

This preferred embodiment is illustrated in the accompanying drawings in which:

FIG. 1 is a schematic perspective view of the apparatus of this invention, and

FIG. 2 is a side-elevational view, partially in cross section showing the apparatus of FIG. 1.

DESCRIPTION OF THE PREFERRED EMBODIMENT

Referring to FIGS. 1 and 2, the apparatus of this invention includes a drive roll 2 which is mounted for rotation on a shaft 4. The shaft 4 is suitably supported in a machine frame, which is indicated schematically at 6. The shaft 4 may be continuous and may support a plurality of drive rolls at each of a plurality of winding stations provided on the machine frame.

An upper bobbin chuck 8 and a lower bobbin chuck 10 are supported on the machine frame 6 in suitable guides for movement toward and away from the peripheral surface 14 of the drive roll. In the schematic representation of FIGS. 1 and 2, the bobbin chucks 8 and 10 are guided along parallel paths by slots 16 and 18, respectively, so that as the yarn package builds on each bobbin, the bobbin chuck moves away from the bobbin drive roll along the respective slots to accommodate the increase in diameter of the yarn package. Of course, as an alternative, the chucks may be mounted on pivoted arms or may slide along guide bars to allow motion toward and away from the drive roll. In accordance with conventional practice, a spring or other yieldable resistance means urges the yarn

packages into engagement with the peripheral surface 14 with sufficient force to prevent slippage between the yarn package and the drive roll.

A traverse yarn guide 20 is mounted for reciprocating movement along a bar 22 on the machine frame. The guide 20 is driven back and forth along the bar 22 by a cam in accordance with conventional practice.

A pivot arm 24 is mounted at one end on a pin 26 that extends outwardly from the machine frame 6. At the opposite end of the arm, a print roll 28 is supported for rotation on an axle 30 that extends outwardly from the arm 24 substantially parallel to the axis of the shaft 4.

The drive roll 2 has a drive ring 32, which may be in the form of a flange on the roll. The drive ring projects above the peripheral surface 14 a distance greater than the thickness of the yarn being processed. A spring 34 between the arm 24 and the frame 6 urges the roll 28 into engagement with the drive ring 32. In order to avoid slippage between the roll 28 and the ring 32, adequate friction surfaces must be provided. As shown in FIG. 1, a band 36 formed of synthetic elastomeric material is applied to the surface of the roll 28 in alignment with the ring 32. The band 36 assures that torque is transmitted by the ring 32 to the roll 28 without slippage. A band formed of Synthane, a material containing filler materials impregnated with phenolic or melamine resins has been found to be suitable for this purpose.

The diameter of the print roll 28 is selected to substantially span the distance between the traverse guide and the drive roll 2. By positioning the traverse guide close to the surface of the print roll, the yarn is accurately placed on the print roll and variations in the pattern of the yarn on the roll are minimized. The print roll preferably is positioned with respect to the traverse guide and the drive roll such that the yarn is in engagement with the surface of the print roll through at least 90° of rotation of the print roll in passing from the yarn guide to the surface of the drive roll. This relationship avoids slippage of the yarn relative to the surface of the print roll and assures that the pattern is not disturbed in being transferred from the print roll to the drive roll.

In operation, a pair of yarns is laced through the traverse guide 20 and is passed under the print roll 28. One yarn end is wound on the upper bobbin which is supported on the chuck 8 and the other yarn end extends around the surface 14 where it is wrapped on the bobbin that is supported by the bobbin chuck 10. With the print roll positioned such that the band 36 engages the drive ring 32, rotation is imparted to the drive roll 2 by means of the shaft 4 and the yarn is laid on the print roll by the traverse guide in a reciprocating pattern. The yarn in the same pattern is transferred to the surface of the drive roll 2, as indicated by the dotted line 38 in FIG. 1. When at times yarn wrap occurs on the surface of drive roll 2, and yarn is accumulated on the roll, the pivotable mounting of print roll 28 on arm 24 permits the print roll to swing away from the peripheral surface 14 of the drive roll against the urging of spring 34.

The yarns on the exterior surface of the upper package bear against the peripheral surface 14 and the friction between the yarns and the surface 14 imparts rotation to the upper yarn package. Similarly, the yarns

in the lower yarn package are driven by the peripheral surface 14. As the diameter of the respective yarn packages increases, the axis of rotation of the bobbins moves away from the bobbin drive roll by sliding along the slots 16 and 18, in accordance with conventional practice. When the bobbins are filled, the bobbin chucks may be further displaced to the front of the machine, and since the yarns pass around the front side of the drive roll, they are readily accessible to the doffing operator.

The yarn take-up of this invention provides a means for placing the traverse guide close to the print roll, so that the yarn does not pass across large uncontrolled lengths. Also, the yarn passes around the front side of the drive roll to simplify the lacing operation and to permit the use of line shafts for supporting a plurality of drive rolls. Since the print roll is mounted on a pivoted lever and driven directly by the drive roll, there is no need for extensive modifications to existing yarn take-up apparatus to achieve the benefits of this invention.

With a proper selection of diameters of the drive ring and the drive band, it is possible to achieve surface velocity of the bobbin drive roll that is equal or different from the surface velocity of the small print roll. This facility to select differing surface velocities is particularly useful when it is desired to maintain low tension upstream of the winding operation, and relatively higher tension in the yarn as it is wound onto the package. In this way, for example, maximum benefit can be obtained from the action of the yarn compaction devices which operate best at low tensions, while the higher tension developed in the yarn between the print roll and the bobbin drive roll permits the winding of firm, high quality packages. For example, with 100 denier yarn, the print and drive roll peripheral speed can be differentially adjusted to provide a yarn tension of 7 grams upstream of the print roll and 14 grams tension downstream of the print roll, thus giving a higher winding tension than the initial take-up tension.

Because the yarn on the take up of this invention does not pass to the rear of the bobbin drive roll, the take up is particularly suitable for the mounting of devices that permit fully automatic doffing and operation of the take up.

While this invention has been illustrated and described in a preferred embodiment, it is recognized that variations and changes may be made therein without departing from the invention as set forth in the claims.

What is claimed is:

1. Yarn take-up apparatus comprising a bobbin drive roll supported for rotation about an axis, said drive roll having a peripheral drive surface, mounting means for mounting a pair or more of bobbins in position to engage said drive roll at locations spaced from each other around the peripheral surface of the drive roll, traverse guide means adjacent said surface of said drive roll, said traverse guide means being movable axially relative to the drive surface of said drive roll, a print roll intermediate said traverse guide means and the drive surface of said drive roll, means supporting said print roll for rotation about an axis, rotating means for rotating said print roll in timed relation with said drive roll, said supporting means allowing movement of said print roll toward and away from said drive roll surface, and

spring means yieldably biasing said print roll toward said surface, said rotating means including cooperating surfaces on said print roll and drive roll whereby rotation is imparted to said print roll by said drive roll and whereby yarns pass through said traverse guide means and extend around the surface of the print roll and are carried on the surface of the drive roll for winding into a yarn package on the respective bobbin.

2. Yarn take-up apparatus according to claim 1 wherein said supporting means includes an arm and pivot means at one end of said arm, said print roll axis being spaced from said pivot axis, whereby said pivot arm allows swinging movement of said print roll toward and away from said drive roll surface.

3. The yarn take-up apparatus according to claim 1 wherein said drive roll includes a radial flange adjacent

said drive surface, said flange forming a drive ring having a diameter greater than the diameter of said drive surface, said flange being in position to engage said print roll upon movement of said print roll toward said drive surface, whereby rotation is imparted by said flange to said print roll, while maintaining the drive surface of said drive roll spaced from the surface of said print roll.

4. Yarn take-up apparatus according to claim 1 wherein said print roll has a smaller diameter than said drive roll and the surface of said print roll is in close proximity to said traverse guide and arranged to support yarn on at least 90° of arc of the surface of said print roll while said yarn passes from said traverse guide to said drive roll surface.
